United States Patent Office

Des. 212,575
Patented Oct. 29, 1968

212,575

COMB

Nathan L. Solomon, P.O. Box 550,
Englewood, N.J. 07631

Filed Aug. 18, 1966, Ser. No. 3,517

Term of patent 14 years

(Cl. D86—8)

I claim:

The ornamental design for a comb, substantially as shown and described.
